UNITED STATES PATENT OFFICE.

FREDERICK HACKMANN, OF CHICAGO, ILLINOIS.

RAIL-ELEVATING JACK.

Application filed January 21, 1924. Serial No. 687,463.

To all whom it may concern:

Be it known that I, FREDERICK HACKMANN, a citizen of the United States, and a resident of the city of Chicago, in the county 5 of Cook and State of Illinois, have invented certain new and useful Improvements in a Rail-Elevating Jack; and I hereby declare that the following is a full, clear, and exact description of the same, reference being had 10 to the accompanying drawings, and to the numerals of reference marked thereon, which form a part of this specification.

This invention relates to a rail elevating jack adapted for use in railway track construction and comprises a jack adapted for engaging underneath a rail for raising the same.

The invention comprises the novel mechanism and combinations hereinafter described 20 and more particularly pointed out and defined in the appended claims.

In the accompanying drawings which illustrate a preferred form of this invention and in which similar reference numerals refer to similar features in the different views.

Figure 1 is an end elevational view of the rail lifting jack.

Figure 2 is a side elevational view of the lifting jack.

Figure 3 is an enlarged sectional view of the elevating jack with parts in elevation.

Figure 4 is an elevational view of a railroad track illustrating the use of the jack.

Figure 5 is a sectional view upon the line 35 5-5 of Figure 3.

Figure 6 is a detail view of the pawl and ratchet holding mechanism of the jack.

Figure 7 is a side elevational view of a modified form of jack with the rail engaging 40 means removed.

Figure 8 is a top plan view of the same.

Figure 9 is a sectional view upon the line 9-9 of Figure 7.

Referring to the drawings which illustrate 45 one embodiment of this invention, the reference numeral 1 represents the base of the jack. This base is provided with downwardly extending anchoring tangs or the like for anchoring the jack adjacent a rail.

50 A standard 2 rises from the base; the upper end of the standard being bifurcated, one arm 3 of the bifurcation extending above the other and being provided with spaced bearing lugs 4 and 5 that overhang the bifurcation. A jack lever 6 is fulcrumed upon said

standard by means of a shaft 7. This lever is provided with a lower bifurcation for receiving the shorter arm of the standard 2, one arm of this bifurcation is in the form of a laterally offset ratchet wheel 8 having teeth 9 and being journaled upon the shaft 7; the other arm of the bifurcated lever depends below the shaft 7 and then extends at substantially a right angle as indicated at 10. This portion 10 is formed with a pocket or recess at its forward end in which a roller 11 is journaled. The upper end of the lever 6 is formed with a handle 12 for carrying the same, and is also hollow for receiving an operating handle 13 (Fig. 4).

A pawl 14 extends through the lugs 4 and 5 for engaging the teeth of the ratchet wheel 8. A coil spring 15 confined between the lug 4 and a pin 16 extending through the pawl, normally urges the pawl into engagement with the ratchet wheel.

In referring to Figs. 2 and 4 it will be observed that the roller 11 is positioned a certain distance upon one side of the vertical plane passing longitudinally through the supporting shaft 7 of the lever. This distance represents the weight arm of the lever. The arm 10 projects laterally from the side of the lever or is laterally offset so that the jack may be positioned adjacent a rail with the roller 11 engaging under a rail. When the lever has been placed in such a position, it is only necessary to swing the operating handle 13 rearwardly to elevate the rail as shown in dotted lines in Fig. 4. When the rail has been raised, the pawl 14 engaging the ratchet will hold the lever in elevated position, during the swinging of the lever, the pawl 14 rides over the ratchet teeth as is obvious.

95 In Figures 7 to 9, I have illustrated a slightly modified form in which the base 1 is provided with a rear wall 1^a having spaced vertical strips 1^b between which a pawl 16 is pivoted for engaging the ratchet wheel 8^a 100 which is formed upon the lower side of the pivotal portion of the lever instead of upon the upper side as in the first form. The pawl 16 is provided with a lateral lug 17 adapted for engaging a stop lug 18 upon the bearing at the top of the strips 1^b which support the pawl. A counter weight 19 depending from the lower side of the pawl normally holds the same in engagement with the ratchet wheel. A pawl trip lever 20 is 110

journalled upon a rod sustained by the strips 1^b, and is located beneath the pawl 16. This trip lever has an upwardly extending arm 20^a adapted for engaging a depending lug 21 upon the pawl, and a hanger arm 20^b in the form of a foot pedal. The pawl 16 may be thrown out of engagement with the ratchet by stepping upon the pedal 20^b whereby the arm 20^a is swung 10 against the lug 21 for swinging the pawl 16 out of engagement with the ratchet 8^a.

It will be appreciated that the device is very simple and can readily be moved from place to place and when in position will not 15 interfere with a passing train.

I am aware than many changes may be made, and numerous details of construction may be varied through a wide range without departing from the principles of this 20 invention, and I therefore do not purpose limiting the patent granted hereon, otherwise than necessitated by the prior art.

I claim as my invention:

1. In a rail elevating jack having an 25 upstanding bifurcated support, a lever having upon one side thereof a ratchet wheel journalled on said support with said ratchet wheel positioned in said bifurcation, said lever having a laterally offset arm on the 30 other side of said lever from said ratchet wheel, a roller journalled in said arm adapted to engage a rail and means engag-

ing said ratchet wheel to hold said lever in adjusted position.

2. In a rail elevating jack, a standard, a 35 lever pivoted intermediate its ends upon said standard and having a laterally offset arm, a roller journalled in said arm for engaging under a rail, and cooperating means on said lever and standard for holding the former 40 in adjusted position.

3. In a rail elevating jack, a base having a standard, a lever having a forwardly offset portion pivoted upon said standard through said offset portion, a laterally offset arm on said forwardly offset portion below said pivot and extending rearwardly, a roller journalled in said arm for engaging a rail and means for holding said lever in 45 50 adjusted position.

4. In a rail elevating jack, a base having an upstanding bifurcated member, a lever having a lower forwardly offset bifurcated end, a pivot pin passing through said member and through said offset end, ratchet 55 teeth on one fork of said bifurcated end, means engaging said ratchet teeth, a laterally offset arm on the other fork of said bifurcated end, and a roller journalled in 60 said arm for engaging a rail.

In testimony whereof I have hereunto subscribed my name.

FREDERICK HACKMANN.
